UNITED STATES PATENT OFFICE.

MINNIE AGNES PHELPS, OF CHICAGO, ILLINOIS.

COMBINED TOASTER AND WARMING-OVEN.

No. 838,053.

Specification of Letters Patent.

Patented Dec. 11, 1906.

Application filed November 13, 1905. Serial No. 287,023.

To all whom it may concern:

Be it known that I, MINNIE AGNES PHELPS, a citizen of the United States, residing at Chicago, in the county of Cook, State of Illinois, have invented certain new and useful Improvements in a Combined Toaster and Warming - Oven, of which the following, taken in connection with the drawings, is a specification.

10 My invention has for its object the production of a combined toaster and warming-oven which is designed more particularly to be used upon gas or gasolene stoves, although the same may, if desired, be used on a range. 15 As gas-stoves are at present constructed it is not only very inconvenient to toast bread, crisp crackers, warm rolls, or the like, but necessitates lighting the oven-burners and heating a much larger space than is necessary for the purpose desired, thereby consuming an unnecessary amount of gas.

Every housekeeper often has occasion to keep food warm after it has been cooked; but as at present constructed there is no provision made in the gas-ranges for doing so without using the large oven-burners. My invention is designed to meet this requirement, and it is so arranged that it may be used over any of the small burners on a gas 30 stove or range.

In the accompanying drawings, forming part of this specification, and in which like letters of reference indicate corresponding parts, I have illustrated one form of device embodying the essential features of my invention, although the same may be carried into effect in other ways without in the least departing from the spirit thereof, and in these drawings—

40 Figure 1 is a perspective view of my invention. Fig. 2 is a cross-section of the same, showing the cover thereof raised and suspended above the grate. Fig. 3 is a sectional view of the toasting device with the handles removed, and Fig. 4 is a sectional view of a modified form of the hinged members D'.

In carrying out my invention I provide a square, rectangular, or other shaped base A, which is provided with upturned side pieces 50 and which has an aperture A' in the bottom thereof, which is adapted to be placed over the burner of a gas-stove. A removable plate B covers the aperture A' when the device is in use. One side a of the base is provided with hinges a', so that it may be opened

outwardly when desired. Springs a² hold the side a in position when closed. Inwardly-bent flanges b are provided upon the top of the base, which are for a purpose hereinafter described.

60 A grate B', slightly smaller than the base A, is disposed inside thereof. Wires C or the like extend upwardly from the corners of said grate, and secured thereto are the supports C', which are joined to two of the corner-wires C.

Movably secured to opposite sides of the base A are uprights D, which are provided with a plurality of slots d. These uprights D are secured together by the hinged members D', which are each provided with a slot d³, as shown, each of which slots receives a tongue bent at right angles to the end of the opposite member. When secured together, the members D' maintain the uprights D in proper position to be utilized for the purpose hereinafter described.

70 A cover D² is provided which is preferably slightly longer than it is wide and is adapted when turned one way to fit inside of the base A, as shown in Fig. 1, or when turned so that the other side is forward said cover will rest upon the inwardly-turned flanges, thereby providing a larger compartment when the device is used as a warming-oven.

80 A hook d' is secured to one of the members D'. An eye d² is provided near the center of the cover D². By means of the aforesaid hook and eye the cover may be suspended above the toaster when it is desired to remove the articles therefrom.

85 The supports C' are bent inwardly to provide the hook or latch c and bent outwardly to provide the handles c', by means of which the grate B' may be raised or lowered by engaging the latch c into a higher or lower slot d.

In Fig. 4 I have illustrated a modified form of construction for securing together the members D'. In this instance the lower member is provided with an elongated slot e, having a 90 downwardly-bent tongue e'. The upper member is provided with a slot e², also a downwardly-bent tongue e³. When in use, the tongue e³ fits into the slot e and abuts against the downwardly-bent portion e'. A 95 band E holds the two members together, as shown.

100 The operation of the device is as follows: When the toaster is to be used over a gas-burner, the aperture A' is covered with the 105

plate B. If used over a coal fire, the plate B is removed. The bread to be toasted is laid upon the grate B' and set over a fire. After the bread has been sufficiently toasted and it is desired to keep the same hot any length of time before serving, the grate B' is raised by the handles C' and the latches c engaged in higher slots d in the uprights D. The cover D² is then placed over the same, and by placing the device over the fire, which has been turned low, the toast or other articles may be kept hot for an indefinite length of time.

The advantages of my invention will be apparent to those skilled in the art.

15 My device is very simple in construction, comprises few parts, can be easily and cheaply manufactured and placed in position, and is effectual in all respects in the performance of its functions. I contemplate such changes 20 in the details of construction as, for instance, the manner of supporting the uprights and securing the hinged members together. A wire frame might be used instead of the slotted frame forming the uprights D.

25 I claim—

1. In a combined toaster and warming-oven, a base provided with an opening through the bottom thereof, upwardly-turned sides forming a receptacle, a door at 30 one side of said receptacle which is closed when the device is in use, a removable plate in the bottom of said receptacle, a grate and means for adjustably suspending the same above the aforesaid plate, and a cover, substantially as described.

2. In a combined toaster and warming-oven, a base provided with an opening through the bottom thereof, upwardly-extending sides forming a receptacle, one of 40 said sides being hinged to the base, inwardly-turned flanges upon the top of each side of said base, uprights extending from opposite sides of said base, a grate, means for adjustably suspending said grate from the afore- 45 said uprights, and a cover adapted to rest

upon the aforesaid flanges, substantially as described.

3. In a combined toaster and warming-oven, the combination of a base having an opening through the bottom thereof, a removable plate, upwardly-extending sides forming a receptacle, one of said sides being hinged to the base, uprights extending from opposite sides of said base, said uprights being bent at right angles at the top and adapted to be secured together to form a bail or handle, a grate adjustably suspended from said uprights and a cover adapted to fit over said base and grate, substantially as described. 6c

4. In a combined toaster and warming-oven, the combination of a receptacle having an opening through the bottom thereof, a removable plate inside of said receptacle, uprights extending from opposite sides of said 65 receptacle, said uprights being bent at right angles to each other and secured together to form a handle, a grate having upwardly-extending arms for adjustably suspending said grate from the aforesaid uprights, a cover 70 and means for supporting the same upon the top of the receptacle.

5. In a combined toaster and warming-oven, the combination of a receptacle having an opening through the bottom thereof, uprights extending from opposite sides of said 75 receptacle, a grate, arms extending from said grate and adapted to be removably adjusted at different heights above said opening, and an inverted receptacle forming a 80 cover adapted to fit over the aforesaid receptacle, substantially as described.

In testimony whereof I have signed this specification in the presence of two subscribing witnesses.

MINNIE AGNES PHELPS.
